(57) **CLAIM**

The ornamental design for a pacifier strap as shown and described.

DESCRIPTION

FIG. 1 is a top, front, right perspective view of a pacifier strap showing our new design.

FIG. 2 is a top, rear, left perspective view thereof.

FIG. 3 is front view thereof.

FIG. 4 is a rear view thereof.

FIG. 5 is a top view thereof.

FIG. 6 is a bottom view thereof.

FIG. 7 is a left view thereof.

FIG. 8 is a right view thereof.

FIG. 9 is a top, front, right perspective view of another embodiment of the pacifier strap.

FIG. 10 is a top, rear, left perspective view thereof.

FIG. 11 is front view thereof.

FIG. 12 is a rear view thereof.

FIG. 13 is a top view thereof.

FIG. 14 is a bottom view thereof.

FIG. 15 is a left view thereof; and,

FIG. 16 is a right view thereof.

In the drawings, the equal-length broken lines depict portions of the pacifier strap that form no part of the claimed design. The appearance of any portion between the break lines forms no part of the claimed design. The drawings are shaded to indicate contrasting surfaces.

1 Claim, 16 Drawing Sheets
